UNITED STATES PATENT OFFICE.

EDWARD FLAD, OF ST. LOUIS, MISSOURI.

CONCRETE METAL CONSTRUCTION.

No. 845,938.

Specification of Letters Patent.

Patented March 5, 1907.

Application filed December 31, 1904. Serial No. 239,180.

To all whom it may concern:

Be it known that I, EDWARD FLAD, a citizen of the United States, residing at the city of St. Louis, State of Missouri, have invented a certain new and useful Concrete and Metal Construction, of which the following is such a full, clear, and exact description as will enable any one skilled in the art to which it appertains to make and use the same, reference being had to the accompanying drawings, forming part of this specification.

My invention relates to a concrete and metal construction, and more particularly to that form of concrete and metal construction in which a body of concrete or other similar plastic material has embedded therein one or more metal bars provided with projections which increase the grip between the bar and the surrounding material. In order that such projections may be effective to increase the grip between the bar and the material and at the same time prevent tendency to split the material, it is necessary that any plane tangent to the bearing-face of the projection shall make an angle with a plane at right angles to the axis of the bar not greater than the angle of repose between the material of the bar and the surrounding plastic material.

I am aware that concrete and metal constructions have been heretofore used in which the metal bars were of the general description above referred to. In all such cases, however, as far as I am aware, the projections have been arranged on the bar in one of two ways: First, they have been so arranged that they will not be cut by all planes perpendicular to the axis of the bar. Consequently the cross-sectional area of the combed bar and projections will not be uniform throughout the length of the bar. Second, the projections have been as wide or wider than the space between the projections. In either case the metal is not used to the greatest advantage, in the first instance because the projections form no useful part of the bar in resisting tensile or compressive strain and in the second instance because much more material is used in the projections than is necessary, as projections should be of substantially the same strength as the interlocking concrete projections.

The object of my invention is to so arrange the projections on the bar that they can be

placed farther apart than their width and at 55 the same time be cut by all planes perpendicular to the axis of the bar, thus using the metal to the greatest advantage.

I accomplish the above objects by arranging the projection or projections around the 60 bar in the form of a spiral, either singly or doubly, according to circumstances, as will be hereinafter more fully described.

In the accompanying drawings, which illustrate a construction made in accordance with 65 my invention, Figure 1 is a sectional view, on a reduced scale, showing the use of my construction in an arch for a bridge or the like. Fig. 2 is a section on the line 2-2 of Fig. 1. Fig. 3 is a side view of a round bar made in 70 accordance with my invention. Fig. 4 is a diagram showing the developed surface of a bar having the projection arranged in the form of a single spiral. Fig. 5 is a diagram showing the developed surface of a bar having the projections arranged in the form of a 75 double spiral. Fig. 6 is an isometric projection of a square bar provided with projections in the form of a single spiral, and Fig. 7 is an isometric projection of a square bar 80 having the projections formed in a double spiral.

Like marks of reference refer to similar parts in the several views of the drawings.

10 represents the body of concrete in which 85 the bars are embedded. In the present instance this body of concrete is shown in the form of an arch for supporting a bridge or other structure. The bars 11 are preferably square in cross-section and they are arranged 90 within the concrete in the usual manner so as to resist either tensile or compressive strain. The bars 11 are provided with a projection or set of projections 12, forming a spiral. This spiral may be single, as shown in Fig. 6 95 and developed in Fig. 4, or it may be double, as shown in Fig. 7 and developed in Fig. 5. The single form shown in Figs. 4 and 6 may be used in case the spiral is made continuous. Such a continuous spiral is also shown in 100 Fig. 3, in which form, however, a round bar 14 is used in place of the square bar 11. It will be evident that any plane perpendicular to the axis of the bar will cut this spiral projection, and consequently that the spiral 105 projection will form an effective part of the bar to resist both tensile and compressive strain. Such a plane is shown on the line

6-6, and another plane is also shown on the line A-A. The end of the bar shown in Fig. 6 corresponds with the plane on the line 6-6. It will be evident that if the line A-A is moved toward the right or left there will be no change whatever in the net cross-section of the bar and projection.

In practice I prefer to form the bar by rolling the same in the usual manner. Consequently it is impractical to make the projection continuous around the entire bar. This is due to the fact that two sides of the square, or one-half of the round bar, is formed by the same roll, and the other two sides of the 15 square bar, or the other half of the round bar, by a second roll, and it is not practical to accurately maintain the relative position of the two rolls. The result is that the projections will be offset, as shown in Figs. 5 and 7. In 20 such a construction if the projections were arranged in the form of a single spiral it would be evident that all the planes perpendicular to the axis of the bar would not cut equal sections of the projection, owing to their offset form. For example, the line C-C in Fig. 5 cuts only a portion of the complete cross-area of the projection 12. In order to 25 overcome this difficulty, I arrange between the turns of the spiral 12 a second spiral 13. It is evident by this construction that the 30 difficulty referred to is entirely overcome. The opposite parts of the two sets of projections are necessarily offset the same amount, and consequently when less than the complete 35 cross-section of the spiral 12 is cut a correspondingly greater amount of the cross-section of the spiral 13 will be cut. In this manner I am enabled to so arrange the two sets of diametrically opposite projections in 40 a double spiral that an equal amount of the projections will be cut by all the planes perpendicular to the axis of the bar, and consequently the bar will have the same strength as a plane bar of equal weight and length.

45 In the specification and claims where I have used the term "concrete" I wish to be understood as including cement or other equivalent plastic material which may be used in the same manner as concrete.

50 Having fully described my invention, what I claim as new, and desire to secure by Letters Patent of the United States, is -

55 1. In a concrete and metal construction, a body of concrete having a metal bar embedded therein and provided with a spiral projection or projections, the bearing-surfaces of said projection or projections forming with a plane at right angles to the axis of the bar an angle not greater than the angle of 60 repose between the bar and concrete, said projection or projections also forming an effective part of said bar to resist tensile or compressive strain.

65 2. In a concrete and metal construction, a body of concrete having embedded therein a

metal bar provided with a plurality of projections, the bearing-surfaces of said projections forming, with a plane at right angles to the axis of the bar, an angle not greater than the angle of repose between the bar and the concrete, said projections being narrower than the spaces between them, and said bar and projections together having substantially the same cross-section at all points in the length of the bar.

70 3. In a concrete and metal construction, a body of concrete having a metal bar embedded therein, said bar being provided with a spirally-arranged projection or projections, the bearing-surfaces of which form with a plane at right angles to the axis of the bar an angle not greater than the angle of repose, said projection or projections being arranged to be cut by all planes perpendicular to the 75 axis of the bar.

80 4. In a concrete and metal construction, a body of concrete having a metal bar embedded therein, said bar being provided with a spirally-arranged projection or projections, the bearing-surfaces of which form with a plane at right angles to the axis of the bar an angle not greater than the angle of repose, said bar and projection or projections having together substantially the same cross-section 85 at all points in the length of the bar.

90 5. In a concrete and metal construction, a body of concrete having a metal bar embedded therein, said bar being provided with projections arranged in the form of a double spiral, the bearing-surfaces of said projections forming with a plane at right angles to the axis of the bar an angle not greater than the angle of repose, said projections being arranged to be cut by all planes perpendicular to the 95 axis of the bar.

100 6. In a concrete and metal construction, a body of concrete having a metal bar embedded therein, said bar being provided with projections arranged in the form of a double spiral, the bearing-surfaces of said projections forming with a plane at right angles to the axis of the bar an angle not greater than the angle of repose, said bar and projections together having substantially the same cross-section at all points in the length of the bar.

105 7. In a concrete and metal construction, a body of concrete having a metal bar embedded therein, said bar being provided with projections arranged in two diametrically opposite sets to form a double spiral, the bearing-surfaces of said projections forming with a plane at right angles to the axis of the bar an angle not greater than the angle of repose.

110 8. In a concrete and metal construction, a body of concrete having a metal bar embedded therein, said bar being curvilinear in cross-section and being provided with a projection or projections, the bearing-surfaces of which form with a plane at right angles to the axis of the bar an angle not greater than 115

the angle of repose, said projection or projections being arranged to be cut by all planes perpendicular to the axis of the bar.

9. In a concrete and metal construction, a body of concrete having a metal bar embedded therein, said bar being circular in cross-section, and being provided with a projection or projections the bearing-surfaces of which form with a plane at right angles to the axis of the bar an angle not greater than the angle of repose, said projection or projections being arranged to be cut by all planes perpendicular to the axis of the bar.

10. In a concrete and metal construction, a body of concrete having a metal bar embedded therein, said bar being curvilinear in cross-section, and being provided with a spiral projection or projections, the bearing-surfaces of said projection or projections

forming with a plane at right angles to the axis of the bar an angle not greater than the angle of repose.

11. In a concrete and metal construction, a body of concrete having a metal bar embedded therein, said bar being circular in cross-section, and being provided with a spiral projection or projections, the bearing-surfaces of said projection or projections forming with a plane at right angles to the axis of the bar an angle not greater than the angle of repose.

In testimony whereof I have hereunto set my hand and affixed my seal in the presence of the two subscribing witnesses.

EDWARD FLAD. [L. S.]
